ROTOR CASTING MACHINE

Edward F. Dolan, Los Angeles, and Henry C. Mellon, Pasadena, Calif., assignors to U. S. Electrical Motors, Inc., a corporation of California

Application January 16, 1931, Serial No. 509,072

12 Claims. (Cl. 22—68)

Our invention relates to the art of casting and relates to a device for casting bus-bars in the rotors of synchronous motors. Although our invention has a wide variety of uses, we are at the present time employing it in the casting of 5 rotors for electric motors. These rotors are made with a laminated core of stamped plates with notches in their edges aligned so as to form bus-bar channels in the periphery of the rotor in which the bus-bars are formed by casting a 10 metal, such as aluminum, therein. At the ends of the rotor and the ends of the bus-bars, bus-bar connector rings and fan blades are integrally formed with the bus-bars. These fan 15 blades or vanes produce a circulation of air and are in direct contact with the air. In addition to this, the fan blades are integrally formed with the bus-bars and the bus-bar connector rings so that heat generated therein due to a 20 flow of electric energy through the bus-bars and bus-bar connector rings is readily conducted to the fan blades by which it is dissipated into the 25 circulating air.

It is an object of our invention to provide a 25 casting device which is especially adapted to casting of the electrical elements in motor rotors by introducing melted aluminum through the base or bottom plate of the mold and raising the aluminum therein so as to completely fill the 30 mold without formation of air spaces therein.

A further object of the invention is to provide a device of this character which will automatically free the end plates of the mold from the casting and will remove the metal gates formed at the lower end of the casting in the 35 inlet openings of the mold, thereby considerably reducing the labor involved.

It is a further object of the invention to provide a simple form of device for applying the melted metal to the mold under pressure. In the preferred form of this device a cylinder is formed under the mold, and a piston is operable vertically within the cylinder to upwardly displace and force into the mold the greater portion of a 40 quantity of melted metal with which the cylinder has been charged preparatory to a casting operation. It is preferable to place in the cylinder a quantity of melted metal greater than required in the casting. When the casting operation is completed, therefore, a residue or disc of metal remains in the upper portion of the cylinder and is connected to the casting through the gate portions formed in the gates of the mold. The invention provides means for preventing raising of the residue from a specified 45

position and means for raising the casting with sufficient force to break off the gate portions as the final step in the casting operation, making it then possible to easily remove the mold and casting from the casting device. 5

A further object of the invention is to provide a means for engagement of the residue with the piston in such a manner that the residue cannot be removed from the piston except in a lateral direction. This enables the residue to be held 10 down while the casting is being raised, thereby severing the residue from the casting in the manner above described.

A further object of the invention is to provide a casting machine having a mold with end pieces, 15 means for holding the parts of the mold tightly together during the introduction of solidifiable material thereinto, and means for moving the end pieces of the mold outwardly so as to free them from the casting. 20

In the preferred practice of the invention the mold is made with a central part and two end plates. In the operation of the casting device the upper end plate is first lifted so as to be freed from the upper end of the casting, and the central part of the mold is then lifted from the lower end piece so as to free the lower end of the casting 25 from the end piece.

Further objects and advantages of the invention will be made evident throughout the following part of the specification. 30

Referring to the drawings, which are for illustrative purposes only,

Fig. 1 is a vertical cross section through a casting device embodying the principles of our invention, this view showing the base and superstructure of the casting device. 35

Fig. 2 is a partly sectioned view showing the injector piston in partly raised position.

Fig. 3 is a view showing the head in raised position, for the purpose of illustrating the manner in which the device functions to free the end plates and sever the gate portions from the casting. 40

Fig. 4 is an enlarged cross section on a plane 45 represented by the line 4—4 of Fig. 1.

Fig. 5 is an enlarged cross section on a plane represented by the line 5—5 of Fig. 1.

Fig. 6 is a fragmentary view showing the injector piston in fully raised position. 50

Fig. 7 is a plan view corresponding to Fig. 6.

Figs. 8 and 9 are perspective views showing the liner members.

In the preferred embodiment of our invention shown in Fig. 1, we provide a base or table struc- 55

ture 11 supported on legs 12, and superstructure 13 supported on posts 14. The device employs a movable head 15 including a vertical bar 16 having a piston 17 on its upper end which is received 5 in a cylinder 18 formed in and supported by the superstructure 13. The lower end of the cylinder 18 is closed by a plate 19 having a packing means 21 for preventing leakage around the bar or shaft 16 so as to enclose a pressure chamber 22 adjacent 10 the lower face of the piston 17, and upper and lower pipes 23 and 24 communicate with the upper pressure chamber 25 and the lower pressure chamber 22 for admitting fluid under pressure to the respective chambers so as to selectively 15 raise and lower the head 15. The table 11 is provided with an opening 26 in which a metal reservoir cylinder 27 is supported in such position that the upper end of the cylinder 27 is substantially level with the upper face of the 20 table 11. In the cylinder 27 is an injector piston 28 which is secured to the upper end of a connecting rod 30 which projects through packing means 31 supported in a plate 32 which is secured to the lower end of the cylinder 27 by means 25 such as screws 33. On the lower end of the connecting rod is an actuating piston 34 which is received in an actuating cylinder 35 having upper and lower pipes 36 and 37 communicating with the upper and lower pressure chambers 38 30 and 39 thereof. Fluid under pressure may be applied through the pipes 36 and 37 to produce upward and downward movement of the piston 34, which movement is transmitted through the connecting rod 30 to the piston 28 of the reservoir 35 cylinder 27. The practice of the invention employs a source of fluid under pressure and valves for controlling this fluid in a manner to selectively operate the pistons 17 and 34, but in view of the fact that such devices are old and well 40 known, illustration thereof is thought unnecessary.

A mold 41, consisting of a central cylindrical part 42 and upper and lower end pieces or plates 43 and 44, is disposed between the reservoir cylinder 27 and the head 15. The central portion of this mold, as shown in Fig. 4, is formed of cooperating halves 45 and 46 which are hinged together by means of a hinge pin 47 and a clamp 48. The clamp 48 is hinged by means of a pin 50 to a lug 51 projecting from the part 45 and has a clevis portion 52 adapted to swing over a lug 53 projecting from the part 46. When the clamp 48 is swung outwardly, the central part 42 of the mold 41 may be opened by swinging the 55 cooperating halves 45 and 46 outwardly on the hinge pin 47. The interior cylindrical face of the central part 42 is of such diameter that it will closely fit the rotor punchings 54 and has the ends thereof counterbored, as indicated at 60 55 and 56, to receive the end pieces 43 and 44 which are provided with a suitable cooperative configuration. The upper end plate 43 is secured to the head 15 by means of a flange 57 which is removably secured in place by means of a set screw 58. Downwardly extending from the flange 57 are lifting hooks 60 having inwardly extending portions 61 at their lower ends which project under a radially extending flange 62 or other similar projection on the central part 42 of the mold 41. 65 The hook members 60 are hinged to the flange 57 at 63, and compression springs 64 operate between the upper ends 65 of the hook members 60 and brackets 66 on the flange 57 to resiliently hold the members 61 of the hooks 60 in inward position. 70

Each of the end plates 43 and 44 has a central boss 67 adapted to engage the assembly of punchings 54, and around each boss 67 is an annular channel 68 from which inwardly extend recesses 70 for molding vanes or fan blades 71 on the rotor. The recesses 70 in the upper plate are provided with vent openings 72 which communicate with an annular channel or passage 73 on the lower face of the flange 57, this passage 73 having continuation openings 74 extending upwardly therefrom through the flange 57. 10

The lower end piece 44 is preferably provided with an annular shoulder 75 adapted to fit in a counterbore 76 in the upper end of the cylinder 27, and upwardly tapering gates 77 are extended from the lower face of the end piece 44 to the bottom ends of the recesses 70. A centralizing pin 78 extends upwardly from the lower end piece 44 and serves to axially align the punchings 54. When the mold is closed, as shown in Fig. 1, the upper end of the pin 78 is received in a concentric opening 80 in the lower end of the boss 67 of the upper end piece 43. The upper portion of the injector piston 28 is provided with a dovetail slot 82 the side walls of which diverge from one end to the other so that a body of metal which hardens in the slot can be removed laterally without binding so as to resist removal but cannot be raised from the piston 28. 20

In the operation of the device the following procedure is followed: A bottom insulator 84 of the shape shown in Fig. 9 is placed in the cylinder 27 on and in engagement with the upper face of the piston 28. This insulator consists of a sheet of asbestos paper having the central portion 35 thereof folded so as to form a dovetailed tapered groove which will fit into the groove 82 in the upper face of the piston 28. The sides or wings 86 of the insulator 84 are circular segments of such size that the upper face of the 40 piston 28 is substantially covered. A wall insulator 87, consisting of a rectangular sheet of asbestos paper rolled to cylindrical form as shown in Fig. 8, is then placed in the cylinder above 45 thereby insulating the metal walls of the reservoir from the melted metal, such as melted aluminum. In the ends of the groove 82 small bodies of asbestos fiber are placed to insulate the portions of the walls of the cylinder 27 exposed at the ends 50 of the groove 82 and under the lower edge of the cylindrical insulator 87. A body 88 of melted aluminum is then placed in the reservoir provided by the cylinder 27, and the center part 42, with the punchings 54 therein, and the lower 55 end piece 44 are moved into position under the head 15 and under the upper end piece 43. Then, by introduction of fluid into the upper pressure chamber 25 of the cylinder 18, the head is forced downwardly and presses the upper end piece 43 into the center part 42 of the mold 41 tightly together. The assembly of punchings 54 is compressed between the bosses 67 of the upper and lower end pieces 43 and 44. At this time air or other fluid under pressure is introduced through the pipe 37 into the lower pressure chamber 39 of the actuating cylinder 35, causing the piston 34 to impel the piston 28 upwardly so as to upwardly displace the body of melted aluminum through the gates 77 into the 70 interior of the mold 41. As shown in Fig. 2, this body of melted aluminum is displaced upwardly within the mold as indicated at 90 so as to displace all of the air in the spaces of the mold and to completely fill the mold. 75

It is a feature of the invention to provide a number of narrow recesses 92 in the side walls of the center part 42 of the mold into which a portion of the melted aluminum will enter as shown 5 and will therein solidify so as to form means for engagement between the casting and the center part of the mold for preventing axial movement of the casting in the center part of the mold during the freeing of the end pieces 43 and 44 from 10 the casting and the breaking of the gate portions 93 consisting of metal solidified in the gates 77. If desired, a pair of hold-down brackets 94 may be employed to hold the lower end piece 44 down during the raising of the head, but in 15 the general use of the invention these hold-down brackets are not necessary for the reason that the gate portions 93 are sufficiently strong to hold the lower end piece 44 down during the initial raising of the head to free the upper end 20 piece 43 from the upper portion of the casting formed therein. These brackets are slotted as indicated at 89 in Fig. 5 so that they may be moved inwardly and outwardly.

In Fig. 3 the head 15 is shown in raised position, and in this view the operation of the mechanism in freeing the end pieces from the casting and severing the gate portions 93 is represented. This final operation is accomplished in the following steps: After the melted metal has solidified in the mold under pressure, fluid is delivered 25 through the pipe 24 into the lower chamber 22 of the cylinder 18 to move the head 15 upwardly. As indicated by dotted lines 95' in Fig. 3, a body 95 of solidified metal or residue is 30 formed between the upper face of the piston 28 and the lower face of the lower end piece 44, and this residue is locked to the piston 28 by a dovetail rib 96 cast in the dovetail groove 82 of the piston. The residue 95 cannot therefore 35 be raised from the piston, and the rotor casting cannot be raised without breaking the gate portions 93; therefore, the first upward movement of the head 15 results in freeing the upper end plate 43 from the upper end of the casting and 40 lifting the upper end piece into a position above the upper vanes 97 of the rotor casting, as shown in Fig. 3. At this time the hook members 60 engage the flange 62 so that the continued upward movement of the head 15 results in pulling the 45 lower portion of the casting upwardly relative to the lower end piece 44 and further results in severing the gate portions 93 on the plane where these gate portions join the lower ends of the lower vanes 98 of the rotor casting. 50

By introduction of fluid through the pipe 36 into the upper chamber 38 of the cylinder 35, the piston 34 is caused to move the piston 28 downwardly so as to carry the residue 95 downwardly therewith as indicated in full lines, this downward movement of the residue 95 resulting in removal of the gate portions 93 from the gates 77, whereupon the center part 42 and the lower end piece 44 may be removed laterally from position under the head 15. The piston 28 is then 55 raised into an upwardly projecting position, as indicated in Fig. 6, so that the residue 95 is supported in position above the top of the table 11, whereupon force exerted against the residue in the direction indicated by an arrow 100 in 60 Fig. 7 will result in the tongue or rib 96 sliding rearwardly in the groove 82 and the residue 95 moving in a lateral and rearward direction from engagement with the piston 28. The piston 28 is then lowered to fully retracted position, as 65 shown in Fig. 1, ready for a consecutive casting 70

75

operation. The gates 77 and the gate portions 93 converge upwardly, thus making the smallest diameter of the gate portions 93 adjacent the points at which they meet the lower ends of the vanes 98. As a result of this upward convergence, 5 the gate portions 93 cannot be pulled through the gates 77, and therefore breakage occurs at the upper ends of the gate portions 93 when the casting is moved upwardly with the center part 42. The bodies of metal extending into the recesses or grooves 92 in the center part 42 of the mold positively move the casting upwardly with the center part 42 when the center part 42 is raised by the hook members 60. Upon removal 10 from position under the upper end piece 43, the 15 center part of the mold may be opened and removed from the casting and then closed and replaced on the lower end piece 44 ready for a consecutive casting operation.

Although we have herein shown and described 20 our invention in simple and practical form, it is recognized that certain parts or elements thereof are representative of other parts or elements which may be used in substantially the same manner to accomplish substantially the same results; therefore, it is to be understood that the invention is not to be limited to the details disclosed herein but is to be accorded the full scope 25 of the following claims.

We claim as our invention:

1. A casting device of the character described, including: a table member having an opening; a reservoir communicating with said opening; a mold adapted to be placed over said opening, said mold having an upper end piece, a central part, 30 and a lower end piece, said lower end piece having a gate opening therethrough communicating with said reservoir in said table member; means for forcing metal from said reservoir through said gate opening into the interior of said mold; an 35 upwardly movable member adapted to hold the parts of said mold together, said upwardly movable member being secured to said upper end piece so as to raise said upper end piece therewith; means carried by said upwardly movable 40 member for engaging and lifting said central part after said upper end piece has been moved a predetermined distance; and means for moving said upwardly movable member.

2. A casting device of the character described, including: a table member having an opening; a reservoir communicating with said opening; a mold adapted to be placed over said opening, said mold having an upper end piece, a central part, and a lower end piece, said lower end piece having 50 a gate opening therethrough communicating with said reservoir in said table member; means for forcing metal from said reservoir through said gate opening into the interior of said mold; an upwardly movable member adapted to hold the 55 parts of said mold together, said upwardly movable member being secured to said upper end piece so as to raise said upper end piece therewith; hook members for lifting said central part after said upper end piece has been moved a predetermined distance; and means for moving said upwardly movable member.

3. A casting device of the character described, including: a table member having an opening; a reservoir communicating with said opening; a 70 mold adapted to be placed over said opening, said mold having an upper end piece, a central part, and a lower end piece, said lower end piece having a gate opening therethrough communicating with said reservoir in said table member; means 75

- for forcing metal from said reservoir through said gate opening into the interior of said mold; an upwardly movable member adapted to hold the parts of said mold together, said upwardly movable member being secured to said upper end piece so as to raise said upper end piece therewith; hook members for lifting said central part after said upper end piece has been moved a predetermined distance; means for moving said upwardly movable member; and means for holding said lower end piece substantially immovable during the raising of said central part of said mold.
4. A casting device of the character described, including: a table member having an opening; a reservoir communicating with said opening; a mold adapted to be placed over said opening, said mold having an upper end piece, a central part, and a lower end piece, said lower end piece having a gate opening therethrough communicating with said reservoir in said table member; a piston vertically movable in said reservoir for forcing melted metal through said gate opening into the interior of said mold, there being a dovetail slot in the upper face of said piston; and means for upwardly moving in consecutive order said upper end piece and said central part.
5. A casting device of the character described, including: a table member having an opening; a reservoir communicating with said opening; a mold adapted to be placed over said opening, said mold having an upper end piece, a central part, and a lower end piece, said lower end piece having a gate opening therethrough communicating with said reservoir in said table member; a piston vertically movable in said reservoir for forcing melted metal through said gate opening into the interior of said mold, there being a dovetail slot in the upper face of said piston; means for upwardly moving in consecutive order said upper end piece and said central part; and insulating means for insulating the upper face of said piston from the melted metal placed in said reservoir, said insulating means having a wall portion bent so as to rest against the walls of said dovetail slot in the upper end of said piston.
6. A casting device of the character described, including: a table member having an opening; a reservoir communicating with said opening; a mold having an upper end piece, a central part, and a lower end piece, said lower end piece forming a removable closure for said opening and having a gate opening formed therethrough for providing a passage from said opening to the interior of said mold; means for holding said mold parts in casting position during a casting operation; means for forcing melted metal from said reservoir through said gate opening into the interior of said mold so as to form a casting therein; and means for separating said casting from said upper and lower end pieces and from the solidified portion of said metal remaining in said reservoir; said separating means including, means for holding said casting within said central part of said mold, means for releasably locking said lower end piece to said table member, a member movably supported with respect to said table member, means responsive to a movement of said movably supported member for consecutively separating said central part and the casting retained therein from said upper end piece and from said lower end piece and the solidified metal retained thereby within said reservoir, and means for moving said movably supported member.
7. A casting device of the character described, including; a table member having an opening; a reservoir communicating with said opening; a mold having a main body and a lower end piece; said lower end piece forming a removable closure for said opening, and having a gate opening therethrough for providing a passage from said opening to the interior of said mold; means for holding said mold parts in casting position during a casting operation; means for forcing melted metal from said reservoir through said gate opening into the interior of said mold so as to form a casting therein; and means for separating said casting from said lower end piece and from the solidified portion of said metal remaining in said reservoir; said separating means including, means for holding said casting within the main body of said mold, means for releasably locking said lower end piece to said table member, a member movably supported with respect to said table member, means for locking said main body of said mold to said movably supported member so as to move therewith, and means for moving said movably supported member so as to separate said main body of said mold and the casting retained therein from said lower end piece and the solidified metal retained thereby within said reservoir.
8. A casting device of the character described, including; a mold having a pair of end pieces and a central part; means secured to one of said end pieces for supporting a core member within said mold; supporting means having a pair of relatively movable members for holding the parts of said mold in casting position during a casting operation; and means for separating said end pieces and said core supporting means from the core and the casting formed thereon, said separating means including means for locking said casting to said central part, one of said end pieces being secured to one of said relatively movable members, the other of said end pieces being secured to the other of said relatively movable members, and means for producing a separating movement of said relatively movable members with respect to each other and with respect to said central part so as to free said end pieces from said casting and core member retained within said central part.
9. In a machine for casting conducting metal into cooperative relation with respect to a stack of laminations, a mold body adapted to enclose a stack of laminations, a common movable means for closing one end of the body and for compressing said stack, means for passing molten metal into the mold body, and means whereby movement of said common means in mold opening direction permits only a limited motion between said common means and the mold body, after which the common means lifts the mold body.
10. In a machine for casting conducting metal into cooperative relation with respect to a stack of laminations, a mold body adapted to enclose a stack of laminations, a common movable means for closing one end of the body and for compressing said stack, means for passing molten metal into the mold body, and means whereby movement of said common means in mold opening direction permits only a limited motion between said common means and the mold body, after which the common means lifts the mold body, said means being disengageable at will from the mold body to permit further motion between said common means and the mold body.
11. In a machine for casting molten metal, a mold body, movable means for closing one end

of the body, means for passing molten metal into the mold body, and means whereby movement of said movable means in mold opening direction serves, at the beginning of the movement, to separate said movable means and said body, and means for limiting the extent of separation between said movable means and said body whereby the movable means lifts the body upon continued movement of said movable means.

10 12. In a machine for casting conducting metal into cooperative relation with respect to a stack of laminations, a mold body adapted to enclose a stack of laminations, a common movable means

for closing one end of the body and for compressing said stack, a support for the body, means for passing molten metal into the body, said body having one or more recesses whereby it is temporarily keyed by the metal to the casting, and means whereby movement of said common means in mold opening direction permits a limited relative motion between said common means and said body, further movement of said common means lifting said body together with its keyed 10 casting off the support.

EDWARD F. DOLAN.
HENRY C. MELLON.
